(57) **CLAIM**

The ornamental design for a pair of zipper parts, as shown and described.

DESCRIPTION

FIG. 1 is a front elevational view of one part of a pair of zipper parts showing my new design;

FIG. 2 is a rear elevational view of FIG. 1;

FIG. 3 is a left side view of FIG. 1;

FIG. 4 is a right side view of FIG. 1;

FIG. 5 is a top plan view of FIG. 1;

FIG. 6 is a bottom plan view of FIG. 1;

FIG. 7 is a first perspective view of FIG. 1;

FIG. 8 is a second perspective view of FIG. 1;

FIG. 9 is a third perspective view of FIG. 1;

FIG. 10 is a front elevational view of the other part of the pair of zipper parts;

FIG. 11 is a rear elevational view of FIG. 10;

FIG. 12 is a left side view of FIG. 10;

FIG. 13 is a right side view of FIG. 10;

FIG. 14 is a top plan view of FIG. 10;

FIG. 15 is a bottom plan view of FIG. 10;

FIG. 16 is a first perspective view of FIG. 10;

FIG. 17 is a second perspective view of FIG. 10;

FIG. 18 is a third perspective view of FIG. 10;

FIG. 19 is a first perspective view showing the pair of zipper parts in a use state;

FIG. 20 is a second perspective view showing the pair of zipper parts in a use state;

FIG. 21 is a third perspective view showing the pair of zipper parts in a use state; and,

FIG. 22 is a fourth perspective view showing the pair of zipper parts in a use state.

The broken lines in FIGS. 19-22 depict environment and are for illustrative purposes only and form no part of the claimed design.

1 Claim, 22 Drawing Sheets
